[57] CLAIM

The ornamental design for a cover for an automobile seat, as shown and described.

DESCRIPTION

FIG. 1 is a perspective view of a cover for an automobile seat showing my new design;
FIG. 2 is a front elevation view thereof;
FIG. 3 is a left side elevation view thereof;
FIG. 4 is a plan view thereof;
FIG. 5 is a rear elevation view thereof;
FIG. 6 is a right side view thereof; and,
FIG. 7 is a front and side perspective view of an alternate embodiment thereof, the other side being the same as disclosed in FIG. 3 and the rear being the same as disclosed in FIG. 5 except for a double indicia.
